MECHANICAL IGNITION

Filed Feb. 2, 1921

UNITED STATES PATENT OFFICE.

ALVAH L. POWELL, OF MILES CITY, MONTANA, ASSIGNOR TO THE A. L. POWELL POWER CO., INC., OF MILES CITY, MONTANA, A BODY CORPORATE.

MECHANICAL IGNITION.

Application filed February 2, 1921. Serial No. 441,977.

To all whom it may concern:

Be it known that I, ALVAH L. POWELL, citizen of the United States, residing at Miles City, in the county of Custer and 5 State of Montana, have invented certain new and useful Improvements in Mechanical Ignition, of which the following is a specification.

My invention relates to improvements in 10 mechanical igniters in which I secure a temperature high enough to effect combustion in an inflammable gas, vapor, or fluid, by direct compression of air. In the accompanying drawings I show a form of my 15 improvement, and also its application to ordinary internal combustion engines.

Fig. 1 is a sectional elevation of one of my mechanical igniters.

Fig. 2 is a cross section on the line 2—2, 20 Fig. 1.

Fig. 3 shows a method of attaching and operating one of my igniters to an ordinary internal combustion engine.

Fig. 4 shows another method of using the 25 igniter on an engine.

Figure 5 is a detail view.

In Fig. 1, a casing, A, preferably shaped as shown, is threaded to a valve fitted member, A¹. The stem of A is bored and a 30 piston, A⁵, is slidably fitted therein. This piston has packing rings, A⁷, A⁷, to assure tightness. Through the upper part of A a hole, B¹, runs to the valve space over A³. The latter is a check valve, preferably held 35 on its seat by a spring, A⁹. Holes by which exhaust from A⁸ may take place are shown at A¹⁰. A removable plug, B, gives access to valve A³. On a plane with the hole B¹, but on opposite side of bored piston chamber, a check valve A², fits to a seat, as 40 shown. Through the opening A⁸ air may be drawn as now to be described.

Let the stem of piston A⁵ be drawn outward, that is, in direction of arrow B³. 45 Valve A² will lift, admitting a charge of air through A⁸ and filling the space above piston A⁵. On forcing the piston back until shoulder A⁶ coincides with stem of A at B⁴, the pressure of the contained air will 50 be augmented and its temperature raised. The degree of this will be governed by the compression. It is here assumed that the diameter of piston A⁵ is sufficiently small to allow a high compression with a minimum

amount of power, in order to get the desired 55 heat at one stroke.

On stem of valve A³ is fitted a spring, A⁹, that holds it on its seat. This valve is relatively small in diameter, so that comparatively little force is needed to lift it 60 and permit the exhaust of the hot air. The heated air, in contact with gas, oil or vapor, will cause ignition.

In Fig. 3 the piston of the igniter is cam operated, from any shaft on an engine, and 65 gas may be indrawn through pipe C² instead of air, this igniting spontaneously from compression and entering engine combustion chamber when tappet on valve A³ is struck at C by engine piston. 70

In Fig. 4 a further method of applying the igniter to an engine is shown. In this, the igniter is placed on side of engine and is operated by a curved bar, from piston. This would operate on either a two or a 75 four cycle engine, for in the latter case the fact that igniter fired on every instroke would not effect its operation, the power consumed being small and the waste charges not affecting the order of functioning of 80 power piston strokes.

What I claim is new and ask to have protected by Letters Patent is—

1. In a mechanical igniter, a casing having a bored passage, a piston slidable in said bored passage, an inlet valve, an outlet valve set at right angles to said bored passage and communicating therewith, removable means for inserting said valve, a spring on the outlet valve for holding it to its seat, 85 means for operating said piston, and means for lifting said outlet valve by the impact of the top of an engine piston, substantially as described. 90

2. In a mechanical igniter, a casing having a bored passage and with a threaded section for insertion in the wall of an engine cylinder, a piston slidable in said bored passage, an inlet valve, an outlet valve set at right angles to said bored passage and communicating therewith, removable means for inserting said valve, a spring on the outlet valve for holding it to its seat, means for operating said piston, and means for lifting said outlet valve by the impact of 95 the top of an engine piston, substantially as described. 100

3. In an internal combustion engine, a

mechanical igniter consisting of a casing having a bored passage, a piston slidable in said bored passage, an inlet valve, an outlet valve set at right angles to said bored

5 passage and communicating therewith, removable means for inserting said valve, a spring on the outlet valve for holding it to its seat, means for operating said piston,

and means for lifting said outlet valve by the impact of the top of the piston of said ¹⁰ internal combustion engine, substantially as described.

In testimony whereof I affix my signature.

ALVAH L. POWELL.
